UNITED STATES PATENT OFFICE.

CHARLES W. BLAKESLEE, OF NORTHFIELD, ASSIGNOR TO NATHANIEL WHEELER, OF BRIDGEPORT, CONNECTICUT.

IMPROVEMENT IN KNITTING-MACHINES.

Specification forming part of Letters Patent No. 44,365, dated September 20, 1864.

To all whom it may concern:

Be it known that I, CHARLES W. BLAKESLEE, of Northfield, in the county of Litchfield and State of Connecticut, have invented certain new and useful Improvements in Circular-Knitting Machines; and I do hereby declare that the following is a full, clear, and exact description of the same, reference being had to the accompanying drawings, forming part of this specification, in which—

Figure 1 is a plan view of the needle-plate, needles, and sinkers of a machine illustrating my invention. Fig. 2 is a central vertical section of a machine complete with the exception of the stand. Fig. 3 is a perspective view of one of the needles and one of the sinkers, showing the manner in which they are combined. Fig. 4 is an inverted plan of the adjustable needle-operating cam and sinker-adjuster.

Similar letters of reference indicate like parts.

The object of my invention is to afford facility for what is termed "narrowing and widening" the work in circular-knitting machines by bringing the parts nearer to or farther from the center of the machine and by reducing and increasing the number of loops in the circular courses.

The invention consists, principally, in the employment, in a circular-knitting machine, of separately adjustable sinkers so applied in combination with the needles as to provide for their being set nearer to or farther from the center of the machine and for the removal of any number of them at pleasure.

It also consists in making the needle-operating cam adjustable for bringing the needles nearer to or farther from the center of the machine, and in a device for adjusting the sinkers in a larger or smaller circle.

It further consists in so combining the needle-operating cam, the device for adjusting the sinkers nearer to or farther from the center of the machine, the yarn-conductor, and the rotary pressing-burr that they are all adjustable together toward and from the center of the machine.

A is the circular needle-plate, having radial grooves *a a* in its face for the reception of the straight shanks *b b* of the sinkers *c c*. The sinkers are of the kind commonly used in those circu-

lar-knitting machines in which stationary sinkers are employed, and are made each in the same piece with its respective shank, or otherwise rigidly secured thereto. The shanks are fitted to move lengthwise in the grooves *a a*, and their upper sides are grooved longitudinally for the reception of the needles *d d*, which are fitted to slide freely therein toward and from the center of the machine. The needles which I propose generally to employ are those of the latched kind. The needles have the rear or outer ends of their shanks turned up, as shown at *e*, to enter the groove *f* of the cam *B*, by which the operation of the needles is produced; and the sinker-shanks have secured in them or formed upon them beyond the needle-shanks upright pins *g*, to enter a groove, *h*, in the sinker-adjuster *C*, which is formed in the same piece with the cam *B*. The said cam and sinker-adjuster are both secured to a slide, *D*, which is fitted into a radially-arranged parallel-sided cavity, *i*, provided in the under side of the rotating circular plate *E*, which covers the needle-plate. This plate *E* is made with a deep rim, *j*, which laps over the edge of the needle-plate, and it is held down closely upon the needle-plate by means of two or more screws, *k*, screwing through the rim *j* and entering a groove, *l*, in the edge of the needle-plate. This plate *E* serves both to confine the needle-shanks in the grooves of the sinker-shanks, and to confine the sinker-shanks in the grooves *a* of the needle-plate, but it does not interfere with the longitudinal movements of the needles or sinkers. The lower edge of the rim *j* of the said plate *E* is cogged to gear with a bevel-gear, *F*, on the driving-shaft *G* of the machine.

H is the rotary pressing-burr, and *I* is the yarn-conductor, both attached to a rigid stock, *J*, which is firmly secured to the slide *D*, hereinbefore mentioned, to which the needle-operating cam and the sinker-adjuster are secured. This slide *D* has a screw, *L*, so fitted to it within the plate *E* that by turning the said screw by a knob, *L'*, provided on it outside of the plate, the said slide, and with it the needle-operating cam, the sinker-adjuster, the burr, and the yarn-conductor, are adjusted toward and from the center of the machine.

The form of the groove *f* in the needle-operating cam is substantially the same as in

other circular-knitting machines in which the needles have a longitudinal movement.

The groove *h* in the sinker-adjuster has both its inner and outer sides of an arc form, as shown in Fig. 1, but the radius of its outer side is so much greater than that of the inner one that the groove is somewhat wider at both ends than at the middle of its length, as shown in Fig. 4, the object of which is to enable the said groove to receive the pins *g g* as it comes round to them after the adjuster *C* has been moved nearer to or farther from the center. The centers of the two arcs are on the same radial line passing through the center of the plate *E* and the length of their radii such that when set at an average distance from the center of the plate they will be nearly concentric therewith.

In the operation of the machine the needles have a movement toward and from the center of the machine, as in other circular-knitting machines, but the sinkers are not intended to have any movement except for the adjustment of the machine for knitting on a circle of larger or smaller circumference, when needles, sinkers, burr, and yarn-conductor are all moved together by the screw *L*, as before described. The sinkers are severally held stationary during the greater portion of the revolution of the machine merely by their friction in the grooves *a a*, as they are not subject to any considerable pressure except while the knitting is taking place on their respective needles, when they are held firmly in place by the reception of their pins or projections *g* in the groove *h* of the adjuster. When the points are shifted by means of the screw *L* to reduce the circumference of the circle of the knitting, or, as it is termed, to "narrow," the shifting is always gradual, and never so great but that

the widening of the ends of the groove *h*, as shown in Fig. 4, will enable it to receive the pins or projections *g* of the sinkers, and that a substantially similar widening of the ends of the groove in the needle-operating cam will enable the said groove to receive the projections *e* of the needle-shanks without fail.

By removing the plate *A* any number of the needles, with their respective sinkers, are permitted to be taken out of the machine and replaced whenever desired.

Before removing a needle upon which the work remains the loop should be taken from it and put onto the next needle on either side.

What I claim as my invention, and desire to secure by Letters Patent, is—

1. The employment, in a circular-knitting machine, of separately-moving sinkers, so applied in combination with the adjustable needles as to provide for their being brought severally nearer to or farther from the center of the machine, substantially as herein specified, for the purpose of widening or narrowing, as set forth.

2. Fitting the needles into grooves in the shanks of the sinkers, substantially as and for the purpose herein specified.

3. The grooved sinker-adjuster *C*, applied to operate substantially as and for the purpose herein described, in combination with projections *g* on the sinkers.

4. So combining the needle-operating cam, the sinker-adjuster, the yarn-conductor, and the rotary burr that all are adjustable together toward or from the center of the machine, substantially as herein set forth.

CHARLES W. BLAKESLEE.
